US00D800903S

(12) **United States Design Patent** (10) **Patent No.:** **US D800,903 S**
(45) **Date of Patent:** **** Oct. 24, 2017**

(54) **SURGICAL TOOL**(71) Applicant: **Medtronic PS Medical, Inc.,**
Louisville, CO (US)(72) Inventor: **Zachary Heiliger**, Golden, CO (US)(73) Assignee: **Medtronic PS Medical, Inc.,**
Louisville, CO (US)(***) Term: **15 Years**(21) Appl. No.: **29/554,155**(22) Filed: **Feb. 9, 2016**(51) LOC (10) Cl. **24-02**

(52) U.S. Cl.

USPC ..... **D24/144; D24/147**(58) **Field of Classification Search**USPC D24/127, 133, 135, 144, 146, 147;
606/29, 32, 33, 47, 48, 50, 81, 82, 171;

(57) **CLAIM**

The ornamental design for a surgical tool, as shown and described.

DESCRIPTION

FIG. 1 is an isometric view of a surgical tool in accordance with principles of the present disclosure;
FIG. 2 is a right side plan view thereof;
FIG. 3 is a left side plan view thereof;
FIG. 4 is a bottom plan view thereof;
FIG. 5 is a top plan view thereof;
FIG. 6 is a rear plan view thereof; and,
FIG. 7 is a front plan view thereof.
The dash-dot lines shown in FIGS. 1-5 illustrate a boundary line that forms no part of the claimed design.

1 Claim, 6 Drawing Sheets
